STOCKLESS ANCHOR

Edgar Duerr, Anglesey, Wales

Application December 29, 1936, Serial No. 118,070
In Great Britain January 18, 1936

1 Claim. (Cl. 114—208)

This invention relates to improvements in or relating to anchors of the stockless type having a single fluke pivoted between a double shank, and limited in movement to approximately 45 degrees 5 on either side by stops.

Whereas it is usual to provide tripping pieces, or an enlarged head to the fluke, to ensure the latter taking hold of the ground, which by their shape unfortunately prevent the complete burying of the fluke and head even in soft ground, this invention has for one of its objects the designing of the tripping pieces, the double shank, and the fluke itself, so as to present a narrow or streamlined edge in the direction of diving of the 10 fluke, a further object being the provision of an anchor which is light in weight for its holding power, and both easy to handle and stow.

In the accompanying drawing, showing an embodiment of the invention:

20 Figure 1 is a vertical section; Fig. 2 shows a side view of the anchor being hauled up over the projections of the boat's planking; Fig. 3 is a section through the fluke; and Fig. 4 shows position taken up by anchor under heavy strain in soft 25 ground.

In the drawing *a* are the tripping pieces, *b* a suitable form of double shank; *c* the trunnion bolts; *d* a hole in head of fluke for attachment of tripping line shackle.

30 The tripping pieces *a* (Fig. 1) which also act as stops limiting the angle of the fluke, are located in line or directly behind the double shank pieces *b* which latter are constructed of narrow section metal of considerable width, which gives 35 great strength against working stresses and at the same time allows the double shank itself to sink below the surface in soft holding ground, rather than drag.

Fig. 2 shows the anchor in position for hauling 40 aboard from which it will be obvious that there is nothing to foul any part of the ship's side,

the rounded tripping pieces sliding easily over uneven or painted surfaces without causing injury thereto.

The anchor when stowed on deck, rests on three widely separated points, and is therefore stable. 5

With this anchor in its normal working position with the fluke only, driven in the ground, the back or upper surface presents a smooth surface, which it is impossible to foul with the cable on change of wind or tide.

10 No matter how carelessly the anchor is let go, the point of the fluke will commence to dig itself in as soon as there is pull on the anchor. Referring to Fig. 2, it will be seen that the construction of the tripping stops is such that the point of contact with the shank is at a sufficient 15 distance from the point of pivot to make this construction exceptionally strong. I do not limit myself to the exact form of fluke shown, but may use any suitable streamlined form, nor do I limit 20 myself to the exact form of double shank, and may use a bridge piece connecting the double shank at any convenient point, or bring the double shank closer together for use with hawse 25 pipes.

I claim:—

A stockless anchor comprising a bifurcated shank, a crown pivoted between the bifurcations of the shank and a fluke member and a disc shaped tripping piece rigid with said crown at 30 each side of the crown disposed in alignment with the respective shank bifurcations and having recesses therein whereby stops are formed limiting pivotal movement of the crown and fluke, that portion of said crown lying between said disc 35 shaped tripping pieces being of relatively small dimensions with respect to the diameter of the tripping pieces facilitating the digging in of the anchor.
